UNITED STATES PATENT OFFICE

WARREN F. BLEECKER, OF BOULDER, COLORADO, ASSIGNOR, BY MESNE ASSIGNMENTS,
TO WILLIAM J. CHELEY, OF TULSA, OKLAHOMA

METHOD FOR INDICATING DETONATION OF EXPLOSIVE CHARGES

No Drawing.

Application filed February 9, 1926. Serial No. 87,176.

This invention relates to a method for indicating exteriorly of an oil well or other similar excavation the operation and condition of a charge of explosive within the same. It is a well known fact that in "shooting" oil wells with nitroglycerine or other high explosive, there is always a question of doubt as to whether or not the charge is exploded in the proper manner and at the proper time, owing to the absence of reliable phenomena at the outside of the excavation and that in consequence there is the ever present possibility of there being a retarded or incomplete explosion with the attendant danger to the operatives who, in the belief that the explosion has taken place, proceed with the work of cleaning out the well.

Aside from the personal risks attendant with the lack of knowledge of the true condition of the explosive in the bottom portion of the well, there are also to be considered the loss of time and possible destruction of valuable equipment, when in the event of failure of detonation or incomplete combustion of the explosive charge, its detonation is later effected by contact of tools lowered into the well for excavation purposes.

At present there is, to the best of my knowledge, no reliable means for ascertaining the true condition of a shot at the bottom of the well. The sound of the explosion, if at all discernible to those on the surface, cannot be depended on to indicate detonation or the condition of the charge, for, particularly in deep wells, the explosion can often not be heard with any degree of distinctness if at all, and any function or disturbance that may occur at the surface is seldom proportionate to the size of the charge. A small shot may cause a loud noise or a big flow of oil and gas, while a larger charge may make little or no sound and cause but little vibration or other indication by which its detonation may be recognized.

Measurements resorted to to ascertain the condition of a shot at the bottom of a well are likewise unreliable because the well may be caved or bridged so as to destroy the only available means of indicating by computa-

tion whether or not the shot was completely or even partially exploded.

In view of the above related facts, the value and merits of a reliable, unfailing method of automatically indicating at the surface of the ground the true condition of an explosive charge in the bottom portion of a well will be readily appreciated.

The object is attained in a simple and efficient manner by the present invention which, briefly, consists in providing in association with a charge of explosive lowered in a well, an element which as a result of the explosion creates a condition at the surface readily detectable either directly or indirectly by the human sensory organs.

Certain combinations of chemicals, for example, of a kind not normally present in the well, will by the concussion or by the heat or by the flame of the explosion, be detonated, ignited or so changed as to release vapors, fumes or matter in gaseous suspension which may find their way to the outlet of the well in quantities of such appreciable magnitude as to be discernible either directly by the human sense organs or indirectly by physical or chemical means.

One form of my invention, perhaps preferable by reason of its simplicity and effectuality, consists in the provision of chemicals or combinations of chemicals which by the action of heat give rise to fumes or vapors which produce fog-like clouds occupying volumes many times greater than the solid or liquid substances from which they originated and which upon emergence from the well are readily seen and give unmistakable evidence that the explosion has occurred. Other chemicals in like manner create odors which are detectable in great dilution by the organs of smell, and still other chemicals give rise to fumes which can be detected in very minute quantities by physical or chemical means and recognized indirectly by the human sensory organs. Among the agents last referred to may be mentioned radio active elements which in great dilution are recognizable by means of an electroscope, vaporized or atomized chlorides which can be detected by contact with solutions of silver;

vaporized or atomized sulfate recognizable by contact with solutions of barium; acids which are detected by coming in contact with blue litmus; alkalis, the presence of which may be determined by contact with red litmus, etc.

5 Among the useful compounds directly detectable by sight or smell or both sight and smell are chloride of iron, chloride of zinc, chloride of manganese and chloride of tungsten. It is not essential that the metals be provided and used as a chloride since certain chemicals either singly or in intermixture with others will produce chlorides by the action of heat. For example, a mixture of calcium chloride and iron tungstate when heated 10 to one thousand degrees Fahrenheit or more, will produce the black vapors of iron and tungsten chlorides. In short any chemical agent capable of producing the desired result may be used by itself or in intermixture with other different agents, with variable results as to the nature of the vapors created upon explosion of the charge—low fusible salts of inorganic base metals and particularly chlorides being preferable for the reason that they are easily vaporized.

In practice, the chemicals in a sealed or otherwise inert quantity, are lowered into the well in connection with the main explosive 30 charge and in such a manner that the explosion will release or otherwise activate the same. The released or activated chemical will find its way to the outlet of the well either intermixed with the gases resulting from the 35 explosion of the charge or the natural gases issuing from the well or both.

The chemicals may be used in any quantity calculated to produce the desired result, it being desirable to allow for slight absorption 40 by any fluid, oil or water, that may be present in the well.

In ordinary practice, about five pounds more or less of a mixture of iron chloride and zinc chloride placed in a soldered or otherwise 45 sealed can or shell will produce satisfactory results. The chemical is not released until by the explosion of the charge with which it is connected, its container is shattered when the freed chemicals are vaporized by the heat 50 resulting from the explosion and the released vapors pass upwardly beyond the mouth of the well as hereinbefore explained, where they are readily detected both by their odor and appearance.

55 Or if an alkali such as ordinary lye or sodium hydroxide is used, the resulting vapors issuing from the well may be aspirated by means of suitable apparatus and the presence of the alkali detected in many ways.

60 A factor greatly contributing to the success of my invention is the intense heat generated in the well by the explosion of a charge usually containing from five to a hundred pounds of nitroglycerine within a restricted 65 space.

By reason of this intense heat, the use of an inorganic compound for the purpose of my invention is recommended since any chemical change affecting the oil present in the well by the high temperature conditions, will have no effect upon the chemicals other than to perhaps form a different compound or combination of compounds, the fumes or vapors of which are readily discernible as before. 70

75 While I have mentioned certain chemicals of proven value for the purposes of the present invention, I do not desire to be limited to their use. Any chemical adapted to produce by heat, concussion, or chemical combination readily discernible fumes or vapors, may be employed within the spirit of the invention, it being apparent that the chemical must be of a character not capable of being destroyed or changed by the conditions of the explosion so 80 that its properties will be obliterated, and of a nature different from any chemical substances that may be naturally present in the well.

85 It is further observed that the heat necessary to vaporize the chemical need not be supplied by or in the chemical mixture itself unless the reaction is exothermic and the detonation or ignition is effected by the concussion of the explosion, there being always the heat 90 of the explosion that can be relied on to effect any chemical change required for the purpose. It is therefore possible to use under all conditions, a chemical charge of such nature as to give a maximum efficiency per unit of 95 volume.

Having thus described my invention, what I claim and desire to secure by Letters Patent is:

1. In a signaling device for oil wells, the combination of a well having a natural effluent issuing therefrom, explosive and ignition means in the well, and an inorganic chemical compound adapted to produce by the explosion detectable gases capable of mixing with the natural effluent and thereby be carried to the mouth of the well in a discernible condition. 100

2. In a signaling device for oil wells, the combination of a well having a natural effluent issuing therefrom, explosive and ignition means in the well, and a volatilizable salt of a base metal adapted to produce by the explosion detectable gases capable of mixing with the natural effluent and thereby be carried to the mouth of the well in a discernible condition. 105

3. In a signaling device for oil wells, the combination of a well having a natural effluent issuing therefrom, explosive and ignition means in the well, and a metallic chloride adapted to produce by the explosion detectable gases capable of mixing with the natural effluent and thereby be carried to the mouth of the well in a discernible condition. 110

4. In a signaling device for oil wells, the combination of a well having a natural effluent issuing therefrom, explosive and ignition means in the well, and an element adapted to produce by the explosion indicative means that differ from the gases of the explosion and are capable of mixing with the natural effluent and thereby be carried to the mouth of the well in a discernible condition.
5. In a signaling device for oil wells, the combination of a well having a natural effluent issuing therefrom, explosive and ignition means in the well, and an element adapted to produce by the explosion indicative means that differ from gases naturally present in the well and are capable of mixing with the natural effluent and thereby be carried to the mouth of the well in a discernible condition.

In testimony whereof, I have hereunto affixed my signature.

WARREN F. BLEECKER.
